DESIGN FOR A BOTTLE

Albert C. Meyer, Glenshaw, Pa., assignor to Glenshaw Glass Company, Glenshaw, Pa., a corporation of Pennsylvania

Application December 2, 1938, Serial No. 81,526

Term of patent 14 years

To all whom it may concern:

Be it known that I, Albert C. Meyer, a citizen of the United States, residing at Glenshaw, in the county of Allegheny and State of Pennsylvania, have invented a new, original, and ornamental Design for a Bottle, of which the following is a specification, reference being had to the accompanying drawing, forming part thereof, in which Fig. 1 is a top plan view of a bottle showing my new design and Fig. 2 a side elevational view thereof, the design having the same appearance when viewed from any side of the bottle.

I claim:

The ornamental design for a bottle, as shown and described.

ALBERT C. MEYER.
